TOY BUILDING-BLOCKS.

GEORGE H. CHINNOCK, OF NEW YORK, N. Y.

Letters Patent No. 60,141, dated December 4, 1866; antedated November 26, 1866.

SPECIFICATION.

TO ALL WHOM IT MAY CONCERN:

Be it known that I, GEORGE H. CHINNOCK, of the city, county, and State of New York, have invented a new and useful improvement in Toy or Building-Blocks; and I do hereby declare that the following is a full, clear, and exact description of the same, reference being had to the annexed drawings, making a part of this specification, in which—

Figure 1 is a plan view of two of my blocks, standing upon end, and so placed together as to form a cube, showing the manner in which a letter, a part of which is situated upon the end of each block, is completely represented by their being placed together.

Figure 2 is a perspective view of one of my blocks.

Figure 3 is a plan similar to fig. 1.

Figure 4 is an elevation showing the manner in which my blocks may be employed in building a toy-house.

Similar letters of reference indicate corresponding parts in all the figures.

The object of this invention is to furnish an instructive amusement for children; and it consists in a novel construction of toy or building-blocks, in the form of cubes divided diagonally in planes perpendicular to two of their sides, the blocks having letters or numerals marked upon them in such a way as to admit, in connection with the peculiar shape of the block, of a much greater number of combinations, and to call forth much more ingenuity in their employment, than has been the case with the toy-blocks heretofore devised. To enable others to understand the nature and construction of my invention, I will proceed to describe it, with reference to the drawings.

The blocks are formed simply by dividing cubes diagonally in planes perpendicular to two of their sides, and consequently have their ends three-sided, or triangular in form, as shown at *a*, while two of the sides, *b b*, are square, and the remaining one, formed by cutting through or dividing the cube, as aforesaid, is a rectangular, quadrilateral in shape. This five-sided shape allows the blocks to be arranged with reference to each other in various ways, so as to form a toy-building, which could not be constructed with the ordinary cubical or six-sided blocks. Complete letters or numerals of any desired form or configuration may be marked upon the sides, *b b*, of the blocks, either by first printing them upon paper or other suitable material, and then pasting them to the said sides, or by painting them directly upon the same, or by any other suitable means. Upon each of the triangular sides or ends, *a*, is marked a portion of a letter or numeral, in such a way that when the rectangular quadrilateral sides of two certain blocks are placed together, they form a cube, the letter or numeral, as the case may be, will be formed complete upon the contiguous ends of the two blocks, as clearly shown in figs. 1 and 3. By this construction of the blocks, and the within-described disposition of the letters upon them, great opportunity is afforded for the exercise of the mental faculties, not only in the arrangement of the blocks themselves, as in making toy-buildings and similar objects, but in the selection and joining of those blocks, the ends or sides, *a*, of which are marked with portions of the same letter or numeral, as hereinbefore set forth.

What I claim as new, and desire to secure by Letters Patent, is—

The building-blocks, of the form of the half of a cube, having five sides, in combination with letters or numerals on their surfaces which are whole in themselves, or bisected diagonally, substantially as shown and described, for the purposes specified.

GEORGE H. CHINNOCK.
